UNITED STATES PATENT OFFICE
DOOR OPERATING DEVICE
John A. Platt, Akron, and Frank N. Sneyd,
Stow, Ohio
Application June 12, 1934, Serial No. 730,196
10 Claims. (Cl. 16—80)

This invention relates to a new and improved type of door operating device and has for its primary object to provide such a device which is simple in construction, efficient in operation and inexpensive to manufacture.

The device is preferably adapted for use in conjunction with a pivotally supported door and operates to maintain the door in either closed or open position.

Another object of the invention is to provide a device of the type referred to which normally acts upon the door to urge it toward closed position up to a certain point in its opening movement and beyond this point tends to urge the door toward its open position.

Another object of the invention is to provide a device of this type wherein the same resilient or yieldable force cooperates with the door to maintain the latter in both its closed and open positions.

With the objects above indicated and other objects hereinafter explained in view, the invention consists in the construction and combination of elements hereinafter described and claimed.

Referring to the drawings:

Figure 1 is an inside elevation of the upper portion of a door and operating device embodying the present invention;

Figure 2 is a sectional view taken on line 2—2 of Figure 1 showing the door in closed position indicated in full lines and partly open position as indicated in dotted lines;

Figure 3 is a sectional view similar to Figure 2 showing the door in open position indicated in full lines and partly open position as indicated in dotted lines;

Figure 4 is a fragmentary sectional view similar to Figure 2 showing a modified form of operating device embodying the invention;

Figure 5 is an inside elevation of the upper portion of a door and a still further modified form of the operating device embodying the invention; and

Figure 6 is a sectional view taken on line 6—6 of Figure 5.

In the drawings a door operating device embodying the present invention is illustrated showing the preferred forms and comprises a frame 10 or other suitable wall structure having a door opening 11 provided therein of any desirable size, depending upon the purpose for which structure is to be used. A door 12 is pivotally connected at one side to the adjacent side of the frame 10 by means of hinges 13, only one of which is herein shown, and is adapted to normally close

the door opening 11, all of this structure as heretofore recited being of the usual construction and of no pertinency with respect to the invention aside from its cooperation with the door operating device.

Preferably at the upper portion of the door 12 adjacent the hinge 13, a bracket 14 is connected to the inner surface of the door by screws 15 and this bracket has a laterally extending flange 16 at its upper portion. A rigid arm or member 17 has one of its ends pivotally connected at 18 to the flange 16 and may be detachably connected by means of a nut and bolt.

A yieldable member 19 of elastic material as shown in Figures 1 to 3 and of any desirable degree of elasticity is disposed upon the under side of the door opening and has its opposite ends connected at 20 and 21 with the frame or wall structure. This member 19 preferably extends substantially in parallelism with the door 12 when the latter is in closed position. The other end of the rigid member 17 is pivotally connected at 22 to the yieldable member 19 at a point between the fixed outer ends and the connection may be detachably effected by means of a nut and bolt.

The yieldable member 19 should preferably be tensioned slightly so that no slack appears when in its normal position and the portion 23 between the end connection 20 and the pivotal connection 22 should be under greater tension than the portion 24 so that it will constantly exert a pull or force on the rigid member 17 to normally tend to urge and maintain the door in closed position.

When the door 12 is in closed position as shown by full lines in Figures 1 and 2, the rigid member 17 should be disposed beneath the yieldable member 19 and extend substantially in longitudinal alignment which ordinarily would position the axes of the connections 20 and 21, the axis of the pivotal connection 18 and the axis of the pivotal connection 22 all in one vertical plane. This condition is of course preferable, but slight variations will not interfere with the efficient operation of the device. If more initial pull is to be exerted upon the door when in closed position, the pivot 18 should be located inwardly of the plane extending through the pivots 20 and 21, that is, farther away from the inner side of the door.

As the door is forcibly moved toward open position as indicated by dotted lines in Figure 2, the portion 23 of the yieldable member 19 is stretched and further tensioned, thus exerting a pull or force upon the outer end of the rigid

member 17 which tends to move the door 12 about its pivot 13 to closed position and will so move the door in the event the door is released. This condition exists during the first part of 5 the opening movement of the door or until moved to a position such as is indicated by dotted lines in Figure 3 where in the axis of the pivot 13, the axis of the pivot 18 and the axis of the pivot 22 are all in a common plane indicated by the 10 line 25. This position may be termed a dead center in which the tension in the portion 23 of the yieldable member 19 has no effect upon the rigid member 17 and consequently upon the door.

When, however, the door 12 is moved just beyond this so-called dead center, the tensioned portion 23 of the yieldable member 19 exerts a push or force on the end of the rigid member 17 and moves the door to its fully open position as indicated in full lines in Figure 3 unassisted.

20 In moving the door from its open position to its closed position, the same action takes place, that is, that the door is forcibly moved toward closed position against the tension of the portion 23 of the yieldable member 19, and should the door be 25 released it will be returned to its open position up to the so-called dead center position. When the door is moved past this dead center position and released, the tension of the portion 23 exerts a pull or force on the end of the rigid member 30 17 which in turn causes the door to move about its pivot to closed position.

It is not, of course, necessary to have the yieldable member 19 made of elastic material, although this affords a very inexpensive and simple construction. Any means for exerting a pull or force upon the end of the rigid member 17 will suffice, other embodiments being illustrated in Figures 4 to 6 inclusive.

In Figure 4, the yieldable member comprises 40 a pair of coiled springs 26 and 27 arranged in a manner similar to the yieldable member 19 heretofore described. These coiled springs have looped outer ends 28 and 29 respectively which are connected to the under side of the door opening by screws or other suitable means. The inner ends are also looped at 30 and 31 respectively and the inner looped ends are connected together by a bolt and nut and to this connection the outer end of the rigid member 17 may be 45 pivotally connected. The spring 26 may be of a greater tension than the spring 27 and the operation is precisely the same as the arrangement shown in Figures 1 to 3 and heretofore described.

In Figures 5 and 6, a still further modification 55 is illustrated wherein the yieldable member comprises a spring 32, a flexible cable or rope 33 and a weight 34. In this construction one end of the spring 32 is connected to the under side of the door opening at 35 by a screw or other suitable means. The cable 33 has one end connected to the free end of the spring 32 as indicated at 60 36 and passes over a sheave 37 rotatably mounted on the frame or other structure as shown in Figure 5. The weight 34 is connected to the opposite end of the cable and the free end of the rigid member 17 is connected to the cable adjacent the inner end of the spring. In the arrangement as the door is forcibly moved the weight 34 exerts a pull or force upon the free 65 end of the rigid member and tends to urge the door either toward closed position or open position, depending, of course, upon whether the position of the door is one side or the other with respect to the so-called dead center.

70 While we have described the preferred em-

bodiments of the invention, it is to be understood that changes and modifications may be resorted to without departing from the spirit of the invention as defined in the appended claims.

What is claimed is:

1. In combination, a frame having an opening therein, a door pivotally mounted on said frame and adapted to close said opening, a rigid member having one end pivotally connected to said door adjacent its pivot, and a yieldable member having its opposite ends connected to said frame, the opposite end of said rigid member being pivotally connected to said yieldable member between its connected ends, the axis of the pivotal connection between said door and rigid member being normally disposed on or inwardly of a plane extending through the connected opposite ends of said yieldable member.

2. In combination, a frame having an opening therein, a door pivotally mounted on said frame and adapted to close said opening, a rigid member having one end pivotally connected to said door adjacent its pivot, yieldable means supported by said frame and having two points of connection therewith, and means for connecting the other end of said rigid member to said yieldable means between its points of connection whereby the opening of said door is resisted, the axis of the pivotal connection between said door and rigid member being normally disposed on or inwardly of a plane extending through the points of connection on said yieldable means.

3. In combination, a frame having an opening therein, a door pivotally mounted on said frame and adapted to close said opening, a rigid member having one end pivotally connected to said door adjacent its pivot, and a yieldable member having its opposite ends connected to said frame, the opposite end of said rigid member being pivotally connected to said yieldable member between its connected ends, the axis of the pivotal connection between said door and rigid member being normally disposed on or inwardly of a plane extending through the connected opposite ends of said yieldable member, said yieldable member tending to urge said door to closed position during the first part of its opening movement.

4. In combination, a frame having an opening therein, a door pivotally mounted on said frame and adapted to close said opening, a rigid member having one end pivotally connected to said door adjacent its pivot, and a yieldable member having its opposite ends connected to said frame, the opposite end of said rigid member being pivotally connected to said yieldable member between its connected ends, the axis of the pivotal connection between said door and rigid member being normally disposed on or inwardly of a plane extending through the connected opposite ends of said yieldable member, said yieldable member tending to urge said door to closed position during the first part of its opening movement, but tending to urge said door to open position during the latter part of its opening movement.

5. In combination, a frame having an opening therein, a door pivotally mounted on said frame and adapted to close said opening, a rigid member having one end pivotally connected to said door adjacent the pivot of the latter and normally in substantial parallelism with said door, and a yieldable member having its opposite ends connected to said frame, the opposite end of said rigid member being pivotally connected to said yieldable member intermediate its ends, the axis

of the pivotal connection between said door and rigid member being normally disposed on or inwardly of a plane extending through the connected opposite ends of said yieldable member.

5 6. In combination, a frame having an opening therein, a door pivotally mounted on said frame and adapted to close said opening, a rigid member having one end pivotally connected to said door adjacent its pivot, and a yieldable member 10 having its opposite ends connected to said frame, the opposite end of said rigid member being pivotally connected to said yieldable member between its connected ends, the axis of the pivotal connection between said door and rigid member being normally disposed on or inwardly of a plane 15 extending through the connections on the opposite ends of said yieldable member.

15 7. In combination, a frame having an opening therein, a door pivotally mounted on said frame and adapted to close said opening, a rigid member having one end pivotally connected to said door adjacent its pivot, and yieldable means 20 connected to said frame at spaced points between which the other end of said rigid member is pivotally connected, the axis of the pivotal connection between said door and rigid member being normally disposed on or inwardly of a plane 25 extending through the points of connection on said 30 yieldable means, said yieldable means being extended upon the forceful opening of said door to thereby return said door to closed position when the latter is released.

35 8. In combination, a frame having an opening 40 therein, a door pivotally mounted on said frame

and adapted to close said opening, a rigid member having one end pivotally connected to said door adjacent its pivot, and an elastic member having its opposite ends connected to said frame, the opposite end of said rigid member being pivotally connected to said elastic member between its connected ends, the axis of the pivotal connection between said door and rigid member being normally disposed on or inwardly of a plane 10 extending through the connections on the opposite ends of said elastic member.

9. In combination, a frame having an opening therein, a door pivotally mounted on said frame and adapted to close said opening, a rigid member having one end pivotally connected to said door adjacent its pivot, and a spring having its opposite ends connected to said frame, the opposite end of said rigid member being pivotally connected to said spring between its connected ends, the axis of the pivotal connection between 15 said door and rigid member being normally disposed on or inwardly of a plane extending through the connections on the opposite ends of said spring.

10. In combination, a frame having an opening therein, a door pivotally mounted on said frame and adapted to close said opening, a rigid member having one end connected to said door adjacent its pivot, and a pair of springs having their outer ends connected to said frame and 20 their inner adjacent ends connected together, the opposite end of said rigid member being pivotally connected to the interconnected ends of said springs, the axis of the pivotal connection between said door and rigid member being normally disposed on or inwardly of a plane 25 extending through the connections on the outer ends of said springs.
